Attorney.

UNITED STATES PATENT OFFICE.

DANIEL EDWARD HIPWELL, OF LONDON, ENGLAND, ASSIGNOR OF ONE-HALF TO SAMUEL CARTER, OF SAME PLACE.

BUCKLE.

SPECIFICATION forming part of Letters Patent No. 606,627, dated June 28, 1898.

Application filed May 6, 1897. Serial No. 635,310. (No model.) Patented in England July 17, 1895, No. 13,678.

To all whom it may concern:

Be it known that I, DANIEL EDWARD HIPWELL, a subject of the Queen of Great Britain and Ireland, and a resident of 14 Upper 5 Bedford Place, Russell Square, London, England, have invented a certain new or Improved Safety-Buckle, (for which a patent has been obtained in Great Britain, No. 13,678, bearing date of July 17, 1895,) of which the 10 following is a specification.

The object of my invention is to provide means for more easily and tightly securing a belt or strap and for readily fastening the same, while so constructing the buckle that 15 it shall always remain securely locked and appearing as an ordinary buckle until its special mechanism is intentionally operated.

Referring to the drawings which form a part of this specification, Figure 1 is a plan 20 view of a buckle shown closed, specially arranged for a pole-chain release. Fig. 2 is a side elevation of said buckle shown open.

The frame A is preferably shaped as shown, and is provided with the cross-bars 1" 2" 3", 25 the one 3" being made removable, while the other two form integral parts of the frame. The outer curved part 2" has a pocket N formed therein to receive the end of the tongue B", which is connected by the pin K" 30 to the lever H". The outer end of this lever, which is made U-shaped and provided with two free ends, is provided with the clips L". The outer end of this lever H" must be pressed

together at M" in order to release the clips, and then the lever can be raised into the position shown in Fig. 2. As long as the front 35 end of the lever is depressed, as shown in Fig. 1, the outer free end of the tongue B" catches in the pocket N, and is thus locked in position. The swivel O is attached to the tail end 40 of the buckle and by means of which it can be connected to any other part of the harness.

Having now described my invention, what I claim as new, and desire to secure by Letters Patent, is—

In a buckle, the frame provided with two cross-pieces which form integral parts of the frame, the outer one of which is provided with a pocket to receive the front end of the tongue, combined with the forked operating-lever 50 which is pivoted to the frame at its rear end, and is provided with the clips at its outer end, the two outer ends being adapted to be pressed inwardly so as to release the clips; the pivotal rod upon which the lever is pivoted and the 55 tongue which is pivoted to the lever, and which has its free end to catch in the pocket when the buckle is closed, substantially as shown.

In witness whereof I have hereunto set my 60 hand in presence of two witnesses.

DANIEL EDWARD HIPWELL.
